United States Patent Office

Des. 182,976
Patented June 3, 1958

182,976

COLORANT DISPENSER

Kenneth C. Rolin, Lake Villa, Ill., assignor to Rockford Paint Manufacturing Co., Rockford, Ill., a corporation of Illinois

Application September 27, 1957, Serial No. 47,907

Term of patent 14 years

(Cl. D52—2)

Fig. 1

Fig. 2

Fig. 3

Fig. 2 is a side elevational view thereof, the opposite side being a mirror image of Fig. 2;

Fig. 3 is a rear elevational view thereof, and

Fig. 4 is a top plan view.

The dominant features of the design reside in the portion shown in full lines.

I claim:

The ornamental design for a colorant dispenser, substantially as shown and described.
